UNITED STATES PATENT OFFICE.

OBADIAH SEELY, OF SYRACUSE, NEW YORK, ASSIGNOR TO E. C. STEARNS & CO., OF SAME PLACE.

JACK-SCREW.

SPECIFICATION forming part of Letters Patent No. 352,362, dated November 9, 1886.

Application filed January 27, 1886. Serial No. 189,891. (No model.)

To all whom it may concern:

Be it known that I, OBADIAH SEELY, of the city of Syracuse, in the county of Onondaga and State of New York, have invented a new 5 and useful Improvement in Jack-Screws, of which the following is a specification.

This invention relates to an improvement in that class of jack-screws or lifting-jacks which are composed of a base or standard and a lifting-screw which works in a nut secured to the base or standard, and which are provided with means for carrying the jack-screw about and for attaching the capstan-bar to the implement.

My invention has the object to provide a 15 simple device for carrying the jack-screw conveniently and for attaching the capstan-bar to the same; and my invention consists of the improvements which will be hereinafter fully set forth, and pointed out in the claim.

20 In the accompanying drawings, Figure 1 is a side elevation of a jack-screw provided with my improvements. Fig. 2 is a sectional elevation at right angles to Fig. 1.

Like letters of reference refer to like parts 25 in the several figures.

A represents the base or standard of the jack-screw, and B represents the lifting-screw, which works in a nut secured to the standard A.

b represents the head of the lifting-screw, 30 provided with openings c, in which is inserted a bar, D, for turning the screw.

E represents an upright handle arranged on one side of the standard, and connected therewith at its upper and lower ends by webs or

bars e. The handle E is made hollow, so as to 35 form a socket for the reception of the capstan-bar D. As shown in the drawings, the cavity or bore of the handle E extends from end to end of the handle, and the lower end of the bar rests upon a lug or support, f, formed at the lower 40 end of the standard underneath the handle. If desired, however, the lower end of the handle may be closed for the purpose of supporting the bar, and in that case the lug f is dispensed with.

45 The jack-screw is moved about by taking hold of the handle E. When the bar D is not required for turning the screw, it is placed in the hollow handle, as represented in the drawings, and in this manner it is removably attached to the jack-screw in a simple and expeditious manner, thereby preventing the bar from being misplaced or lost.

50 I claim as my invention—

In a jack-screw, a base or standard, A, provided with a hollow handle, E, adapted to receive the capstan-bar, and provided at both ends with webs e, whereby it is secured to the base A, and forming between the webs e a rigid handle, by which the jack-screw can be carried 55 about, substantially as set forth.

Witness my hand this 9th day of January, 1886.

OBADIAH SEELY.
